MULTIPURPOSE COSMETIC CASE
Frank A. Pimentel, 206 South Road, Page Park,
Fort Myers, Fla.
Filed July 19, 1961, Ser. No. 125,162
8 Claims. (Cl. 132—79)

This invention relates to an improved multipurpose self-contained swivel-type make-up case or compact resembling a lipstick case but differing therefrom in that it provides the user not only with a lipstick but rouge, face powder, and suitable applicators therefor.

Multipurpose cosmetic compacts are not new. For example, the Burnett Patent 2,273,559 reveals a handbag-type vanity case having optionally usable facilities such as lipstick, face powder and nail file. The lip and facial rouge compact in the Williams Patent 2,219,000 is also generally indicative of the subject matter of the instant proceeding in that it discloses a barrel or case with end caps, face and lip rouge media and manually shiftable rod with selectively projectible and retractible applicators.

An objective in the instant matter is to improve upon the above mentioned prior patents and any similarly constructed and performing beauty aid compacts and kits. It follows that the instant invention has to do with a novelly constructed sectional multipurpose cosmetic case which offers a user thereof readily applicable and removable caps at both ends of the case, one containing rouge and the other containing face powder in cake form. Then, too, applicators for these selectively usable cosmetics are provided.

Another aspect of the concept which is likewise significant has to do with the cover for that end or section of the case on which said cover is removably fitted. This cover comprises a simple open-ended sleeve provided at an outer end with a detachable rouge-containing cap having a practical and convenient projectible and retractible applicator for the rouge.

Novelty is also predicated on a double-barrel swivel case having a projectible and retractible lipstick at one end, say the inner end, and a detachable cap at the outer end, said cap containing powder in cake form and serving to accommodate a projectible and retractible applicator carrying a powder puff.

Stated somewhat more explicitly the invention is further unique in that the elongated case is made up of swivelly coupled sections or barrels, there being a thimble or a bushing mounted intermediate the ends of the case, the bore of the bushing providing a guide bearing and serving to accommodate a reciprocable rod having a puff equipped applicator on one end and a cup on the other end, said cup constituting a second applicator but, more specifically being provided with a projectible and retractible lipstick.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a view in perspective showing the complete ready-to-use multipurpose cosmetic compact or case;

FIGURE 2 is a view in perspective of the same with the rouge cap removed and the sponge-like rouge applicator projected to a ready-to-use position;

FIGURE 3 is likewise a view in perspective with the case cover removed as shown at the left and wherein the lipstick is shown in its projected ready-to-use position;

FIGURE 4 is also a view in perspective which may be compared with FIGURE 2 except that in this instance the face powder containing cap is shown detached with the

2

projectile and retractible powder puff equipped applicator in its projected ready-to-use position;

FIGURE 5 is an exploded perspective view showing the straight slotted and helically slotted components which constitute more-or-less conventional means for projecting and retracting the lipstick and puff-carrying applicators;

FIGURE 6 is a central longitudinal section on an enlarged scale through the completed device seen in FIGURE 1;

FIGURES 7, 8 and 9 are enlarged cross-sections on the lines 7—7, 8—8 and 9—9 of FIGURE 6;

FIGURE 10 is a similar cross-section looking in the opposite direction and taken on the plane of the section line 10—10 of FIGURE 6; and

FIGURE 11 is a view in perspective of the normally concealed dual purpose projectible and retractible plunger-like applicator unit.

Reference will be made first to FIGURE 3 wherein it will be noted that the double barrel or swivel-type lipstick case is denoted as an entity or unit by the numeral 12. The readily applicable and removable cover is denoted at 14. This cover comprises an open-ended sleeve 18 the inner open end of which is denoted at 16. The outer end of this sleeve is denoted at 20 (FIG. 2) and has a reduced protruding neck 22 provided with at least one radial or peripherally projecting lug 24 constituting a keeper and which is adapted to be rotatably and releasably connected with a bayonet slot 26 in a readily applicable and removable cap 28, said cap being provided in the receptacle portion thereof with a fixed cup 30 containing a first cosmetic preparation; namely, face rouge 32. This first applicator comprises a sponge or the like 34 of prerequisite size mounted (FIG. 6) on a cup-shaped slide 36 telescopingly mounted in the cooperating outer end portion of the sleeve and provided with a bayonet pin carrying a knob 38 operable in a bayonet slot 40. Thus the sleeve or cover 14 is adapted to be removably mounted on the case 12 and in fact stays in position until one desires to use the lipstick 42. In other words this cover may remain in place on the case 12 when one is using the rouge 32 and also the projectible and retractible applicator means 34 and 36. Normally, however, the slide or applicator 36 is retracted and recedes into the outer end portion 20 which, of course, allows the cap 28 to be applied and fastened with the bayonet slot 26 and keeper or lug 24. It is within the purview of the invention to use duplicate bayonet slot and connection on a diametrically opposite side of the cap 28 (as shown in FIG. 7) but this feature is optional. So much for the novel cover or sleeve and its detachable rouge cap and applicator means 34 and 36. Taking up now the double barrel or swivel type case 12 it is to be pointed out, generally speaking, that it is characterized by an inwardly disposed barrel 44 over which the cover 14 is removably and frictionally fitted, this barrel being open at the end 46 to accommodate the projectible and retractible lipstick 42. The outwardly disposed barrel or section 48 is slightly larger in diameter and swivelly mounted and is open at the outer end (righthand end in the drawings), this end being designated at 50 (FIG. 4) and having a reduced neck 52 provided with a lug or detent 54 releasably engageable in the bayonet slot 56 embodied in the rim of a detachable cap 58, this cap also having a receptacle portion provided with a cup 60 fixed in place and containing a supply of face powder in cake form as at 62.

The projectible and retractible applicator means (normally retracted and confined in the hollow portion of the overall barrel or case as shown in FIG. 6) is characterized by a novel unit which will be referred to as a plunger-type applicator unit or means 64 (FIG. 11). This means comprises a linearly straight rod 66 which has a disk-like

head 68 on the righthand end carrying a powder puff 70. The other end is also provided with a head but more specifically a holding cup 72 for the lipstick 42 (FIG. 6) said cup being provided on one side (FIG. 11) with a radially projecting plunger operating lug 74. It should be pointed out here that the means which imparts reciprocating motion to the novel dual applicator unit 64 for projecting either 70 or 42 is old in the art and will be touched upon generally here. As a matter of fact the means is similar to that shown for example in prior Patent 1,749,565 of March 4, 1930 and 2,565,346 of August 21, 1951. The tubular or open-ended cylinder 76 has a straight keying slot 78 in which the lug 74 is fitted as shown in FIGURE 6, said slot opening through the righthand end of the cylinder. This cylinder is fitted telescopically in a companion cylinder 80 having a helical slot 82 opening through the respective ends and also accommodating the key or lug 74. These component parts 76 and 80 are assembled and fitted in cooperative relationship in the barrel or case section 44. The cup 72 is slideable in the cylinder 76 and one end of this cylinder is fixed by a collar or band 84 (FIG. 6) to a reduced end portion of a bushing or thimble 86 having a bore 88 therein and fitting telescopically into a cylindrical liner 90 friction fitted in the barrel section 48. Thus the section 48 and lining 90 constitute a handle to accomplish the swivel action and by holding the barrel 44 and the barrel 48 and turning the two relative to each other (in a well known manner) the applicator means or unit 64 is reciprocated or slid back and forth by reason of the rod 66 slidably mounted in the guide bore or bearing 88. It follows that by removing the cap 28 as shown in FIGURE 2 and operating the finger-grip 38 in relation to the bayonet slot 40 the rouge applicator 34 may be brought into play without, of course, having to remove the sleeve 18 from the barrel 44. In FIGURE 3 (the cover sleeve 18 having been removed) and by catching hold of the handle section 48 and section 44 and swivelling the same the mechanism described and shown in detail in FIGURE 6 comes into play and projects the lipstick 42 for use. This mode of use is brought out in FIGURE 3. In FIGURE 4 it can be assumed that the cover 14 has been applied to its normal position and that the lipstick has been withdrawn or retracted. Then and as shown at the right in FIGURE 4 the cap 58 may be removed and the "handle" 48 rotated in the proper manner to bring the applicator means 64 into action again and in so doing to project the head or disk 68 and powder puff 70 thereon. The puff when properly rubbed on the powder 62 may now be properly brought into use. It should be pointed out here that the aforementioned sleeve 52 (FIG. 4) can be, and preferably is, an integral extension of the fixed cylindrical liner 90.

It is believed that a careful consideration of the specification in conjunction with the views of the drawings will enable the reader to obtain a clear and comprehensive understanding of the construction and arrangement of component parts as well as the attending features and advantages and mode of operation and use. Therefore, a more lengthy description is believed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A compact for selectively usable cosmetics comprising: an elongated cosmetic case embodying inward and outward companion barrels having outer ends which are open, a guide bushing lodged and fixed in said case intermediate the respective open outer ends of said case, dual-acting applicator means of a length less than the

length of said case, said applicator means being normally retracted and concealed in said case and embodying a rod having a median portion thereof slidably mounted in the guide bore of said bushing, one end portion of said rod extending into said outward barrel and terminating in an applicator member which is projectible and retractible relative to the adjacent open outer end of said outward barrel, the other end portion of said rod likewise having an applicator member thereon which is slidably operable in the inwardly disposed barrel, said last-named member being projectible and retractible relative to the open outer end of said inward barrel, extensible and retractible operating means for said applicator means operably confined in the bore of said inward barrel and mechanically connected to said last-named member whereby when said barrels are manually caught hold of and rotated relative to each other, said applicator means, depending on the member which is selected for use, being projectible and retractible, and a readily attachable and detachable cover for said case fitted removably on and enclosing said inward barrel.

2. The structure defined in claim 1 wherein one member comprises a disk, said disk being adapted to support and carry a projectible and retractible powder puff, the other member comprising a cup and said cup being adapted for reception and retention of a complementary projectible and retractible lipstick.

3. A compact for selectively usable cosmetics comprising: an elongated cosmetic case embodying inward and outward companion barrels having outer ends which are open, a lining secured in the bore of the outward barrel and commensurate in length therewith and having one end flush with alike end of said barrel and the other end projecting a minimal distance beyond the outer end and providing a cap mounting neck, a cap mounted and removably fastened on said neck and closing said last-named outer end, a guide bushing lodged and fixed in an end of said lining, said inward barrel being axially aligned with said outward barrel and adjacent ends of said barrels being swivelly joined and manually turnable in respect to each other, dual acting applicator means of a length less than the length of said case and normally housed and concealed in said case, said means embodying a rod having a median portion slidably mounted in the guide bore of said bushing, one end portion of said rod extending into said lining-equipped outward barrel and being provided with an applicator head projectible and retractible relative to the open outer end of said outward barrel, the other end portion of said rod likewise having an applicator head which is projectible and retractible relative to the open outer end of said inward barrel, and extensible and retractible operating means for said applicator means confined for actuation in the bore of the inward barrel and mechanically connected to said second applicator head, whereby when said barrels are caught hold of by hand and rotated relative to each other said applicator means is actuated for selectively projecting or retracting a selected head and a readily attachable and detachable cover fitted removably on and enclosing said inward barrel.

4. The structure according to claim 3, and wherein one head comprises a disk having an outward face which is adapted to be provided with a powder puff.

5. The structure according to claim 4, and wherein the other head comprises an axially reciprocable cup with its receptacle portion facing the open end of said inward barrel and accordingly adapted for reception and retention of a lipstick.

6. A cosmetic compact comprising, in combination, a case embodying an outwardly disposed first barrel open at its outwardly located end, an inwardly disposed second barrel axially aligned with said first barrel and open at its outwardly located end, adjacent ends of said barrels being swivelly joined together, a readily applicable and removable open-ended sleeve slidably and removably

fitted over and enclosing said second barrel, cosmetic applicator means housed and telescopically and retentively but releasably confined in an outer end portion of said sleeve, said applicator means being manually projectible and retractible relative to said outer end portion and normally assuming a fully retracted out-of-the-way position within the confines of said outer end portion, said outer end portion having a protruding neck, a first closing cap removably mounted on said neck, separable fastening means for mounting and retaining said cap on said neck, dual-acting applicator means supplemental to said first-named applicator means and slidably keyed and confined in said case and having selectively actuatable end members projectible at will beyond the respective open outer ends of said barrels, and a second closing cap removably mounted on the open end of said first barrel.

7. A cosmetic compact comprising, in combination, a case embodying an outwardly disposed barrel open at its outwardly located end, an inwardly disposed companion barrel axially aligned with said first-named barrel and open at its outwardly located end, adjacent ends of said barrels being swivelly joined together, dual-acting applicator means of a length less than the length of said case and normally held and concealed in said case, said applicator means comprising a rod having applicator members at opposite ends thereof with said members selectively projectible and retractible at will in respect to the respective open ends of said barrels, bearing means supporting a median portion of said rod, said bearing means being fixedly mounted in a median portion of said case, actuating means for said applicator means operable in the bore of the inward barrel and mechanically keyed to the adjacent applicator member whereby when said barrels are caught hold of and rotated relative to each other, said actuating means and also said applicator means is brought into play for selectively projecting or retracting either of said applicator members, a readily applicable case cover comprising an open-ended sleeve removably

5 mounted on said inwardly disposed barrel, an applicator auxiliary to said dual-acting applicator means and embodying a slide slidably and rotatably mounted in an outer end portion of the sleeve and projectible and retractible in relation to said outer end portion, a first closing cap removably mounted on the applicator-equipped end of said sleeve, and a second closing cap, said second closing cap being removably mounted on support means provided therefor on the open end of the outwardly disposed barrel.

10 8. The structure defined in claim 7 and wherein each cap is removably fastened in its closing position, each cap having an inwardly facing receptacle portion and said receptacle portion containing and enclosing a fixedly mounted cup adapted to contain accessible cosmetic media.
